UNITED STATES PATENT OFFICE.

HERBERT ELLSWORTH, OF CLEVELAND, OHIO, ASSIGNOR TO WILLIAM NOVILLE, OF SAME PLACE.

DESIGN FOR AN UMBRELLA-STAND.

SPECIFICATION forming part of Design No. 28,466, dated April 12, 1898.

Application filed April 27, 1895. Serial No. 547,423. Term of patent 7 years.

To all whom it may concern:

Be it known that I, HERBERT ELLSWORTH, citizen of Canada, residing at Cleveland, County of Cuyahoga, and State of Ohio, have invented a new and original Design for Umbrella-Stands, of which the following is a specification.

The leading features of my design are a pyramidal top resting upon slender columns, which rest in turn upon a raised base representing the lower portion of a pyramid.

The accompanying drawing represents a side elevation of an umbrella-stand which embodies my invention.

1 represents the pyramid at the top of the device, composed of four tiers of inclined series of trapezoids, the central tier 2 being the widest and closely connected with the next adjacent tier 3. The lower tier of trapezoids 4 is separated from the higher tiers by vertical faces 5, crowned by moldings 6.

7 is a conical cap crowning the pyramidal form and terminating in the ball 8.

The columns 10 are circular in cross-section, and their bases and capitals are composed of circular moldings of simple form. The base 11 is terminated above by the nar-

row platform 12, provided with the circular openings 13 and a bead or fillet 14, encircling its edge. Below the base is the footing 15, composed of vertical faces equal in number to the trapezoidal sides of the bases and shorter, so that the base will overhang them. The trapezoids of the base and of the two lower tiers of the pyramidal tops are outlined with the raised strips 16, enhancing their shape.

The general appearance of my design will therefore be that of a small temple or pagoda having an elevated pyramidal portion and an overhanging inclined base separated by slender columns. The central column N, of a larger diameter than the exterior columns, is also provided with a capital and base of corresponding design.

Having thus described my invention, I claim—

A design for an umbrella-stand substantially as shown.

HERBERT ELLSWORTH.
